UNITED STATES PATENT OFFICE.

WILLIAM M. EISEN, OF NEW YORK, N. Y., ASSIGNOR, BY MESNE ASSIGNMENTS, TO THE
ADJUSTABLE ARTIFICIAL LIMB COMPANY, INC., OF NEW YORK, N. Y., A CORPORA-
TION OF NEW YORK.

ARTIFICIAL LIMB.

1,211,423.

Specification of Letters Patent.

Patented Jan. 9, 1917.

Application filed April 25, 1916. Serial No. 93,374.

To all whom it may concern:

Be it known that I, WILLIAM M. EISEN, a citizen of the United States of America, residing at New York city, county and State 5 of New York, have invented certain new and useful Improvements in Artificial Limbs, of which the following is a full, clear, and exact description.

This invention relates to improvements in 10 artificial limbs, the object being to provide an artificial leg provided with a stump-socket that is arranged for vertical, lateral and diametrical adjustment, a further object being to provide the leg with a vertically 15 adjustable ankle and thigh.

The object of providing a vertically adjustable ankle and thigh is to adapt the leg to be lengthened or shortened to suit requirements, a further advantage being that 20 the same leg can be used for persons of different heights by adjusting the ankle or foot portion and thigh-piece relatively to the stump-socket.

The object of providing an adjustable 25 stump-socket is to adapt the said socket to stumps of different sizes.

The foregoing statements are merely outlines of the objects and advantages of my invention, a more particular description of 30 which will follow.

I will now proceed to describe my invention in detail, the essential features of which will be summarized in the appended claims, reference being had to the accompanying 35 drawings, forming part hereof, wherein:

Figure 1 is a side view of an artificial leg embodying my improvements; Fig. 2 is a top plan view of my improved stump-socket; Fig. 3 is an enlarged fragmentary sectional view of the lower end of the stump-socket arranged for amputations below the knee; Fig. 4 is a side elevation, partly in section, of the foot portion of the leg, the lower end of the stump-socket being also shown; Fig. 40 45 50 55 60 65 70 75 80 85 90 95 100 105 110

shown as diametrically adjusted; and Fig. 10 is a side view, partly in section, of the foot portion of the leg, showing a modified form of adjustable connection.

As herein illustrated my improved artificial leg consists of a stump-socket 1 and a foot portion 2, which are held in operative relationship by side braces 3 and 4. My improved socket is adapted both for amputations below the knee and above the knee. 60 When used for an amputation below the knee, the socket will be used in combination with a foot, as shown in Fig. 1. For an amputation above the knee, the socket will carry side braces 5 (one only being shown 70 in Fig. 8) which will be connected at 6 to the side braces of a lower leg section, which may or may not be provided with an adjustable foot portion, such as 2. The socket, as illustrated in Fig. 8, will be referred to 75 later.

As can be seen in Figs. 1 and 2, the socket 1 consists of a plurality of members 7 and 8 which are connected at 9 by an adjustable connection of a nature to permit the members 7 and 8 to be moved toward or away from each other to increase or decrease the internal diameter of the socket. Each member 7 and 8 is provided with bands 10, 10 and 11, 11 respectively, each band 11 carrying a 85 slotted plate 12 which overlaps its corresponding band 10 on the member 7, a set-screw 13 serving to bind the band-members together. The socket-member 7 is further provided with plates 14 having a slot 15 through which threaded studs 16, carried by the section 7 pass (see Fig. 2). The studs 16 also pass through the side braces 3 and 4, as shown, nuts 17 serving to bind the braces and socket together.

To increase or decrease the diameter of the socket 1 for any desired purpose, for instance to accommodate or fit a shrunken stump (it being well known that stumps shrink after an amputation) the set screws 100 13 will be loosened and the member 8 moved toward or away from the member 7, after which the set screws will be tightened up. After the member 8 has been adjusted or moved the center line of the socket will 105 change, hence the socket as a whole will have to be moved to the right or left to bring its center line over the center line of the ankle 18. To shift the socket as a whole, the nuts 17 will be loosened, whereupon the 110

socket can be moved laterally. After the adjustment of the socket, the nuts will be set up to hold the stump and braces firmly together.

5 To increase or decrease the length of the leg, I provide the foot 2 with racks 19 (one only being shown, Figs. 1 and 6) having teeth 20 which are engaged by teeth 21 carried by the braces 3 and 4. The braces 3 and 4 are provided with slots 22, 23, through which set screws 24 pass and engage threaded openings 25 in the racks 20. Nuts 26 serve to keep the teeth 20 and 21 in engagement. To decrease or increase the length 15 of the leg, the nuts 26 will be loosened sufficiently to allow the teeth 20 and 21 to be separated, after which the foot 2 can be moved up or down. After the foot has been adjusted, the nuts 26 will be set up to hold 20 the teeth 20 and 21 in engagement.

As I do not wish to depend entirely upon the side braces 3 and 4 to maintain the stump and foot portions together or in alinement, I provide a supporting post 27 which is 25 carried by the stump-socket and which slidably engages an opening or guideway 28 in the foot 2. In order that the post 27 will not interfere with the adjustability of the stump-socket members, I provide a plate 30 or bracket 29 (Fig. 3) which is secured at 30 to the socket-member 7, but not to the socket-member 8. The post 27 may be integral with the plate 29, or secured to it. The plate 29 and post 27 may be made of 35 aluminum or other light material. The post 27 will take the strain off the braces 3 and 4, and thus provide a rigid structure. I prefer to make the post-supporting plate 29 cup-shaped in order that the end of the 40 stump will not come in contact therewith, as some stumps always remain tender.

For an amputation above the knee, the socket 1 will carry the braces 5 referred to, which are secured to the member 7. To 45 adjust just the lower leg-member with respect to the upper stump, the braces 5 will be provided with slots 31 and 32 through which the threaded studs 16 will pass, the nuts 17 serving to hold the said braces and socket 1 50 together. The socket 1 is capable of being adjusted laterally, for an amputation above the knee, the same as described for an amputation below the knee and for the same purpose, and can be adjusted diametrically 55 in the same manner as described for an amputation below the knee. Fig. 9 illustrates the socket as having been increased in diameter.

Fig. 10 illustrates a modified form of foot 60 adjusting mechanism. In this form I provide the post 27 with a rack 33 having teeth 34 to be engaged by teeth 35 carried by a block 36 removably secured by a set-screw 37 in a socket 38 in the ankle-portion 18 of 65 the foot 2. To adjust the foot 2, the block

36 will be moved out of engagement with the rack 33, after the screw 37 has been removed. When the foot has been adjusted the block 36 will be again caused to engage the rack and held in such engagement by the 70 set-screw 37.

The space between the socket-sections may be bridged or covered by a metal or leather tongue 39, which also acts to protect the flesh at this point (see Fig. 2).

75

Whenever in the foregoing specification and appended claims, I use the term "leg," it is to be understood that any other limb is to be included, as my improvements are also adaptable for use in connection with 80 artificial arms, etc.

Having now described my invention, what I claim and desire to secure by Letters Patent is:

1. In an artificial-leg, a stump-socket-member, a foot-member, braces carried by said socket adjustably secured to said foot member, and an auxiliary support connected at one end to said socket-member and slidably engaging said foot-member at its opposite end.

2. In an artificial-leg, a stump-socket-member, a foot-member, racks carried by said foot-member, braces carried by said socket-member, teeth carried by said braces 95 to engage the teeth in corresponding racks, and releasable means to keep the teeth on said racks and braces in engagement.

3. In an artificial-leg, a stump-socket-member, a foot-member, racks carried by 100 said foot-member, braces carried by said socket-member, teeth carried by said braces to engage the teeth in corresponding racks, releasable means to keep the teeth on said racks and braces in engagement, and an 105 auxiliary support connecting said foot-member and socket-member.

4. In an artificial leg, a stump-socket-member, a socket-plate carried thereby, a foot-member, and a slidable post rigidly and directly connected at its upper end to said plate and having a direct slidale connection with the foot-member at its opposite end.

5. A stump-socket for artificial-legs, consisting of a plurality of separable spaced 115 apart members, means to connect said members arranged to permit of the diametrical adjustment of said members, one of said members being provided with transversely disposed slots for the passage of bolts to 120 engage leg-braces and a post-supporting plate connected to one of said members.

6. In an artificial leg, a foot-member, a stump-socket-member, side-braces connecting said members, and means to adjust the 125 stump-socket-member relatively to the foot-member and independently of any movement of the side-braces.

7. A stump-socket for artificial-legs, consisting of a plurality of separable members, 130

- slotted plates, each secured at one end thereof to one of said members, screws passing through the slots and engaging the other socket-member, one of said socket-members being provided with laterally disposed slots, leg braces for said socket having vertically disposed slots, and securing bolts passing through the slots in the socket-member and the slots in the leg-braces.
10. 8. In an artificial-leg, a stump-socket-member, a foot-member slidably connected thereto, means for adjusting the socket diametrically, and means to shift the center of the socket with respect to the foot-member
- 15 after the diameter of the socket has been changed.
9. In a stump-socket for artificial-legs,

comprising adjustably connected socket-members, a plate located at the bottom of the socket-members but secured to only one 20 of said members, and a supporting-post carried by the plate.

10. In combination with an artificial-leg, a foot-member, a supporting-post slidably connected to said foot-member for vertical 25 adjustment thereon, and means to lock the foot-member and supporting-post in adjusted positions.

Signed at New York city, N. Y. this 20 day of April, 1916.

WILLIAM M. EISEN.
